Attorney

UNITED STATES PATENT OFFICE

JOSEPH M. REDINGER, OF PROVIDENCE, RHODE ISLAND

CIGAR LIGHTER

Application filed April 9, 1928. Serial No. 268,757.

This invention relates to certain new and useful improvements in cigar lighters, and the primary object thereof is to provide a cigar lighter which has novel means for holding the wick cap or snuffer in closed position.

In the drawings:

Figure 1 is a side elevation;

Figure 2 is a reverse side elevation partly broken away and in section, and

Figure 3 is a section on line 3—3 of Fig. 1.

In proceeding in accordance with the present invention, a case 1 is employed having the usual plug or closure 2 at its bottom to enable the case to be filled with liquid fuel. A tube 3 is secured at its ends to the top and bottom of the case and receives the flint rod 4 therein, the latter being tensioned by a coil spring 5 which bears against a screw 6. The screw 6 is threaded in the bottom end of the tube 3

and enables adjustment of the tension of the spring, as is obvious. A sparking wheel 6' is mounted on a stub shaft 7. The stub shaft 7 has a knurled head 8. A sleeve 9 is mounted on the shaft 7 and at one end abuts the head 8 while its opposite end portion is formed with a curved guard 10 which partly surrounds the sparking wheel, the latter abutting against a shoulder 12 at the inner side of the guard 10.

The sleeve 9 is mounted in a bearing 13 which latter engages the inner side of the head 8 and the inner side of the guard 10. The bearing 13 is in the form of a head formed on the upper end of a tube 14, the latter having a closed lower end 15 and being formed with a shoulder 16 which engages the top 17 of the case. The sleeve 9 as shown in the

Figures 2 and 3 is formed with a flat face 18 engaged by a plunger 19, the plunger being slidably mounted in the tube 14 and being tensioned by a coil spring 20 therein. The wick 21 extends through a guide 22 mounted on the top of the case and is formed to engage a cap or snuffer 23 secured by an arm 24 to the sleeve 9 and is provided with a handle 25.

In operation it will be seen that upon raising the handle 25 the plunger 19 will be depressed by virtue of the flat face 18 of the sleeve 9 engaging the plunger, and therefore the plunger upon disengagement of the flat

sleeve 9 and hold the wick snuffer in its inoperative position. Upon restoring the wick snuffer to its operative position, it will be seen that the plunger 19 will engage the flat face 18 of the sleeve 9 and will thereby latch the snuffer in position in order to prevent accidental exposure of the wick.

Having thus described my invention what I claim as new and desire to secure by Letters Patent is:—

1. In a cigar lighter, a casing, a wick carried by the casing, a spring tensioned flint rod, a tubular member secured to the casing and having a bearing at its upper end, a spring pressed plunger in the tubular member, a spindle having a head which abuts a side of the bearing, a sparking wheel rigidly secured to the spindle, a sleeve mounted on the spindle and abutting the head thereof and disposed in said bearing, a guard on the sleeve surrounding said wheel and abutting the opposite side of the bearing, said sleeve having a flat face to engage the plunger, a snuffer for the wick connected to said sleeve, and a handle extending outwardly from the snuffer.

2. In a cigar lighter, a casing, a wick carried by the casing, a spring tensioned flint rod, a tubular member secured to the casing and having a bearing at its upper end, a spring pressed plunger in the tubular member, a spindle, a spark wheel rigidly secured to the spindle, a member journaled in said bearing and disposed about the spindle and having a flat face to engage the plunger, a snuffer for the wick secured to the member, and a handle secured to the snuffer.

3. In a cigar lighter, a casing, a wick carried by the casing, a bearing secured to the casing, a sleeve in the bearing, a snuffer for the wick carried by said sleeve, a spindle within the sleeve having a spark wheel thereon, a flint member engaging the wheel, said sleeve having a flat face, and a spring pressed plunger carried by the casing and engageable with said flat face of the sleeve when the snuffer is in inoperative position.

In testimony whereof I have hereunto signed my name to this specification.

JOSEPH M. REDINGER.
